UNITED STATES PATENT OFFICE.

GARY ALLEN GOLDSMITH, OF LONG BEACH, CALIFORNIA.

INDICATOR AND SAFETY COUPLING FOR ROTARY DRILLS.

Application filed February 4, 1924. Serial No. 690,508.

To all whom it may concern:

Be it known that I, GARY ALLEN GOLDSMITH, a citizen of the United States, residing at Long Beach, in the county of Los

Angeles and State of California, have invented new and useful Improvements in Indicators and Safety Couplings for Rotary Drills, of which the following is a specification.

10 My invention relates to drill stems and consists of the novel features herein shown, described and claimed.

An object of my invention is to make a drill stem having means for warning the 15 operators when the stem breaks, and having means for pulling out the lower end of the stem after it is broken.

Fig. 1 is a view in elevation of a drill stem embodying the principles of my invention.

20 Fig. 2 is a diagrammatic view of a drill stem and drill in a well hole, being operated by a rotary rig and showing a break in the drill stem near its lower end so that the lower end 25 of the drill stem will not rotate and showing the application of my invention to warn the operators at the rig that the drill stem is broken and showing the internal connection which is not broken by the rotary strain and 30 which will pull the broken end of the drill stem and bit out of the hole.

Fig. 3 is an enlarged sectional detail diagrammatic of a well hole showing the details of my invention.

35 Fig. 4 is a horizontal cross section on the line 4—4 of Fig. 3 and looking downwardly.

Fig. 5 is a horizontal cross sectional detail through the well casing and drill stem on a line 5—5 of Fig. 3 and looking up- 40 wardly.

Fig. 6 is a perspective of the upper valve plug shown in Fig. 3.

Fig. 7 is a perspective of the lower operating head shown in Fig. 3.

45 Fig. 8 is a view analogous to Fig. 3 and showing a break in the drill stem and showing how the lifting rod connecting the upper valve plug and lower operating head at the opposite sides of the break stops the 50 water circulation to indicate to the operators that the drill stem is broken and forms a connection between the upper part of the drill stem and the broken off part which will lift the broken off part when the drill stem 55 is removed from the well.

Referring to Fig. 1, the bit 1 is connected

to a drill stem section 2 and the coupling members 3, 4 and 5 connect the drill stem section 2 to the drill stem section 6.

Referring to Fig. 3, the coupling members 60 3, 4 and 5 are shown in diametrical longitudinal sectional detail.

The upper end of the member 3 is internally screw-threaded to form the pin box 7 and the screw-threaded pin 8 is screwed into this box. The bore 9 is formed from the upper end of the member 4 and is somewhat larger than the water passage to form a spring seat shoulder 11 and the extreme upper end of the member 4 is bored out and 70 machined to form the internal screw-thread 13.

An expansion spring 14 is mounted in the bore 9. The lower end of the member 5 has a bore 15 matching the bore 9 and an 75 external screw-thread 16 to match the thread 13. The operating head 17 is loosely mounted in the bore 15. A spring seat comprising a disc or washer 18 is placed upon the spring 14. The operating head 17 is a 80 solid cylinder having radial longitudinal ribs 19, said ribs extending below the lower end of the cylinder and resting upon the washer 18. The bores 9 and 15 are sufficient to allow a sliding movement of the operating 85 head on account of the jolts from drilling and to make allowance for variations of the screw threaded connections of the drill stem section and coupling.

The lifting rod 20 is screwed into the upper end of the head 17 and firmly seated by lock nut 21. The upper end of the bore 15 forms a tapered shoulder 22 and a smaller bore 23 extends from the shoulder 22 to the upper end of the member 5. The rod 20 95 extends loosely through the bore 23. The drill stem section 6 is screwed into the upper end of the member 5 and may be of considerable length. The coupling members 24, 25, 26 and 27 are assembled and screwed 100 upon the upper end of the drill stem section 6.

The threads 28 and 29 at the ends of the drill stem section 6 are the ordinary threads used in such work. A bore 30 extends 105 through the member 24. The member 25 is connected to the member 24 by the pin and box construction 31, there being a small bore 32 through the lower end of the member 25 and a larger bore 33 extending from the bore 32 upwardly, there being a valve seat 34 at the junction of the bores 32 and 33.

A valve plug 35 works loosely in the bore 33 and has a valve end 36 to fit the seat 34. The valve head 35 is a cylindrical body having longitudinally extending radial ribs 37 to fit loosely in the bore 33 and allow the water to pass the valve head when the valve is open. The member 26 is connected to the member 25 by the screw-thread construction 38 and has a bore 39 forming an extension of the bore 33 for the valve head 35 to operate in.

The rod 20 is screw-threaded through the valve head 35 and has a jamb nut 40 upon its upper end against the valve head to hold the valve head solidly in an adjusted position. The bore 39 extends some distance into the lower end of the member 26 and a smaller bore 41 extends the remaining distance to the upper end of the member. The coupling member 27 is connected to the member 26 by pin and box construction 42 and a drill stem section may be connected to the upper end of the member 27 in the ordinary way.

The extreme upper end of the drill stem has the ordinary swivel head 43 to which a hose 44 is attached and the other end of the hose 44 is connected to the pump mechanism 45 so as to circulate water downwardly through the drill stem to the bit 46 at the bottom of the well hole. The drill stem 47 is being operated by a rotary rig 48 in the usual way.

It frequently happens in the operation of a drill with a rotary rig that the drill stem breaks and the operators have no notice of the break and so the rig keeps on grinding with the upper part of the drill stem operating and the lower broken off part not operating. Of course this accomplishes nothing but wearing out the equipment.

When a drill stem is equipped in accordance with the principles of my invention and the drill stem section 6 breaks between the upper assembly 48 and the lower assembly 49 of my apparatus, as indicated at 50, the rod 20 will not be broken by the rotation of the upper part of the drill stem and if the upper part of the drill stem is moved upwardly the valve 36 will seat upon the shoulder 34 and stop the circulation of the water and indicate to the operators that the drill stem is broken. Then if the drill stem is raised the rod 20 will lift the broken off end of the drill stem out of the well.

The drill stem section 6 may be of any desired length and there may be any number of the constructions incorporated into a

long drill stem. Usually the drill stems break near their lower ends and leave a short piece of drill stem and the bit in the well hole.

The upward assembly 48 comprises the coupling members 24, 25, 26 and 27, including the valve 35 and the valve seat 34, and the lower assembly 49 includes the coupling members 3, 4 and 5, including the lifting head 17 and the cooperating elements.

Thus I have produced a drill stem comprising an upper assembly of couplings including a valve construction and a lower assembly of couplings having a lifting head with limited upward movement, a string of drill stem sections connecting the assemblies and a lifting rod connecting the valve to the lifting head through the string of drill stems and normally holding the valve open, so that if the string of drill stems breaks between the assemblies and the upper part is raised slightly the valve will close and if the drill stem is removed from the well the broken off part will be raised by the lifting rod.

Various changes may be made without departing from the spirit of my invention.

I claim:

1. A drill stem comprising an upper assembly of couplings including a valve construction and a lower assembly of couplings having a lifting head with limited upward movement, a string of drill stem sections connecting the assemblies and a lifting rod connecting the valve to the lifting head through the string of drill stems and normally holding the valve open so that if the string of drill stems breaks between the assemblies and the upper part is raised slightly the valve will close and if the drill stem is removed from the well the broken off part will be raised by the lifting rod.

2. A drill stem comprising an upper assembly of couplings including a head mounted to reciprocate, and a seat limiting the downward movement of the head, a lower assembly of couplings having a head with limited upward movement, a string of drill stem connections connecting the two assemblies, a spring and a lifting rod connecting the upper head and the lower head said rod being held normally elevated by said spring so that if the string breaks between the two assemblies the lifting rod will raise the parts below the break.

In testimony whereof I have signed my name to this specification.

GARY ALLEN GOLDSMITH.
